1

The present invention relates to a device on an automatic pirn winder for depositing on a pirn skewer board the bobbins ejected by an automatic pirn winder. With multiple-spindle winding machines, pirn skewer boards are used which have a number of pirn skewers or pegs on which the wound pirns are skewered so that, where different colours or kinds of yarn are wound simultaneously, said different colours or kinds of yarn can be collected separately. The pirn skewer board is, in these machines, moved on by one skewer pitch at each pirn change. Now, it is of great importance, especially in weaving-mill practice, that the pirns which are wound with the thread of a large cross-wound bobbin (cheese) should be charged into the loom shuttle in the same order as that in which their winding is effected. In this way, with dyed yarns in particular, fluctuations in the colour of the thread of a cheese are rendered less conspicuous than where the pirns are indiscriminately introduced into the weft.

For this purpose it has been proposed to deposit the pirns in a box, in rotation, by mechanical means. Of the pirns contained in a box, however, only the topmost are visible, and these only from one side, with the result that faultily-wound pirns are not detectable as such. In this respect, pirn skewer boards are more advantageous because they enable the pirns to be inspected.

A cross-wound bobbin (cheese) of the size in common use yields about 50 weft pirns when unwound. These weft pirns should now be skewered on a pirn skewer board in a definite order and be conveyed to the loom together with the skewer board, so that the pirns can be charged into the shuttle in the same sequence as that in which they were unwound from the cheese. But a pirn skewer board accommodating fifty pirns is too large to be guided in the known manner past the stationary pirn-ejection station in both directions, as the space required would be approximately twice the length and twice the width of the pirn skewer board.

The object of the invention is to enable a pirn skewer board for a large number of pirns, say approximately 50 pirns, to be charged with pirns at a pirn winder without the pirn skewer board having to be displaced laterally, so that the necessary space is no greater than that occupied by the pirn skewer board itself. The invention resides in the fact that both the pirn skewer board and the pirn ejection chute are so connected to the frame of the winding machine via

articulations that both units are pivotable about a stationary, imaginary point.

For this purpose, both the pirn ejection chute and the pirn skewer board are, in accordance with the invention, so secured to a winding frame by means of universal joints that angular movements can be imparted to both the pirn ejection chute and to the pirn skewer board, and thereby all the pegs or skewers on the pirn skewer board brought, in turn, into direct alignment with the centreline of the pirn ejection chute and the ejection chute surrenders a pirn to the peg axially aligned with said chute.

In the annexed drawing typical embodiments of the invention are illustrated. In the drawing:

Fig. 1 shows diagrammatically how a pirn skewer board arranged to pivot in two directions about a point, and a pirn ejection chute also pivoted in two directions about a point will serve the end sought;

Fig. 2 shows geometrically two universal joints of which the upper serves to pivot the pirn ejection chute and the lower to pivot the pirn skewer board;

Fig. 3 is a very diagrammatic perspective view of a mechanism having pivoting frame on which a pirn skewer board can be placed, and of the appurtenant, pivoting pirn ejection chute;

Fig. 4 shows in section a form of mouth for the chute, and its curvilinear movement from skewer to skewer;

Fig. 5 shows the mechanical gear of the embodiment here illustrated by which the pirn ejection chute is intermittently shifted from one row of pegs on the pirn skewer board to the adjacent row;

Fig. 6 shows the mechanical gear by which the pirn ejection chute is shifted along the row from one skewer to the next;

Fig. 7 is a view of the mechanical gear to Fig. 6 taken in the direction of the arrow in Fig. 6;

Fig. 8 shows diagrammatically the path described by the pirn ejection chute when charging the pirn skewer board;

Fig. 9 shows a portion of the drive mechanism of the device in conjunction with an automatic pirn-winder, viewed from the side;

Fig. 10 is a plan view of the gearing of the device;

Fig. 11 is a section through a portion of the mechanism of the gear box of Fig. 9;

Fig. 12 is a lateral overall view of the arrangement.

As indicated before, Fig. 1 illustrates the prin-

inciple on which the pirns are directed to the skewers of the skewer board according to the present invention. The delivery device which passes the pirns to the skewers and board is represented in this Fig. 1 by a tube or chute L down which the pirns pass successively by gravity. At Sp a pirn is shown passing from the chute toward a skewer of the board. The delivery device, or at least its discharge portion from which the pirns pass to the respective skewers (the lower end of the chute L in Fig. 1), is so mounted that this discharge portion is movable substantially throughout a solid arc of a solid angle having its apex at a point B. The solid angle is indicated by the side lines C and D and the elliptical lines E and F outlining its base; the lines E and F also indicate the boundaries of the solid arc of Fig. 1. The skewer board H to which the pirns are to be delivered is located at the opposite side of the solid arc E, F from the solid angle apex B, with its skewers or pins pointing toward this arc, and is so mounted that it can be rocked into various planes, each of which is parallel to, but generally at least is spaced somewhat from, a plane that is tangent to the solid arc at some individual point on the arc. In Fig. 1, some of the pins or skewers of the board H are indicated at S. Preferably the board is so disposed that it can be brought into a plane parallel to the plane which is tangent to the solid arc E, F at the center point of the arc and with the center point A of the board substantially lying in a straight line drawn from the apex B to and through this center point of the arc (the position occupied by the board H in Fig. 1), and the board is rocked about this internal point A of it. I. e., this point on the board remains fixed in space as the board is rocked. This arrangement is not altogether essential however, as will become apparent. Speaking generally, the number of planes into which the skewer board can be rocked corresponds to the number of skewers or pins on the board—preferably the number of these planes equals the number of skewers or pins—and each plane is so chosen that when the board lies in the respective plane at least one of the skewers or pins lies substantially normal to the solid arc; i. e. lies substantially in a radius of the arc, or in a radius of the arc extended. At S2 in Fig. 1 are represented two skewers standing in such normal or radial positions. Further, the skewer board H and the discharge portion of the pirn delivery device (for example, the lower end of a chute L), are so connected together that when the board H is brought into any one of the planes which it can occupy, and thereby at least one skewer or pin is brought to a position substantially normal to the solid arc, the discharge portion of the delivery device is brought along the arc correspondingly to a position where it can deliver a pirn to that skewer.

It follows accordingly that by this invention a skewer board can be filled with pirns without the board moving sidewise as it were, and accordingly can be filled within space that is available for the board adjacent winders. Thus for example (and referring to Fig. 8 for example for a numbering of the skewers), the board can be rocked into a plane that places No. 1 skewer normal to the solid arc and correspondingly the discharge portion of the pirn delivery device placed adjacent to this skewer. As soon as a pirn has been delivered to this skewer, the board can be rocked again into an adjacent plane where No. 2 skewer is normal to the arc, and along with

5 this the discharge portion of the delivery device placed adjacent to the No. 2 skewer. When a pirn has been delivered to this No. 2 skewer, the operations can be repeated with respect to No. 3 skewer, and thereafter with respect to No. 4, and so on until the last skewer on the board has received a pirn. When this last has occurred, the filled board can be removed and replaced by an empty skewer board, and at about the same time the board carrier of the device can be rocked to place the No. 1 skewer of the empty board normal to the arc and the discharge portion of the pirn delivery device moved to adjacent the new No. 1 skewer. The whole series of operations then can be started over again.

10 The required movements of the skewer board and the delivery portion of the pirn delivery device are such as to be readily accomplished mechanically. Thus the movement of the discharge portion of the pirn delivery device can be brought about easily by, for example, swinging the tube or chute L of Fig. 1; also the required movements can be given to such guide members for the pirns as L, and to carriers for the skewer boards, by 15 mounting them on universal joints. The principle of this is illustrated in Fig. 2. Fixed bearings 2 carry a member 3 rotatable or revolvable therein on what may be called axis y₁. This member 3 in turn carries a bearing or bearings 5 and 6 in which a member 7 is rotatable or revolvable on what may be called axis x₁, and which also, with the member 3, rotates or revolves about the point B of Fig. 2. The point B of this structure, at the intersection of x₁ and y₁, corresponds to point B of Fig. 1, and by mounting the tube or chute L on the member 7, and operating 20 3 and 7 independently but simultaneously in a manner that will be understood, the lower or delivery end of the chute or pirn guide L can be swept over a solid arc, e. g. the arc E, F, and brought to any selected point on the arc at will. Similarly fixed bearings 16 carry a member 14, say, rotatable therein along what may be called axis y₂, and in turn this member 14 carries bearings 17a in which a member 18 is, say, rotatable about what may be called axis x₂. The member 18 may be the carrier of the skewer boards, on 25 which they are placed successively. The intersection of axis x₂ and axis y₂, or the point where one passes above the other, corresponds to point A of Fig. 1. By turning the members 14 and 18 30 independently but simultaneously in a manner that will be understood, each skewer board can be carried through the rocking movements described with reference to Fig. 1. By interconnecting members 3 and 14, as by arms 3b and 19 and a link V₁ for example, so that they move simultaneously and through, say, equal angles, and by interconnecting members 7 and 18, as by arms 8a and 20 and a link V₂ for example, so that these two members move 35 simultaneously and through, say, equal angles, the discharge portion of the chute or guide L and the skewer board on the carrier 18 at any moment can be made to perform their operations in the relation, one to another, described with reference to Fig. 1. It will be understood of course that only one of the known forms of universal joints has been represented in Fig. 2, and that another of those forms can be substituted readily for the form shown.

tion of the purn delivery device is moved. This distinction between the planes in which the skewer boards may lie and the planes which are usually tangent to the solid arc, is due to the fact that probably, it will be necessary to space the skewer boards from the solid arc somewhat in order that the discharge portion of the purn delivery device may have room to move about without interference from the boards or the skewers on the boards. In so far as, for example, departures of the discharge portion of the purn delivery device from an exact solid arc, or the form of this discharge portion itself, etc., may make spacing of the boards from the solid arc unnecessary, planes of the boards and adjacent tangent planes may approach each other of course until, conceivably, some or all the planes of a board may actually be tangent planes. It is to be understood accordingly that the claims hereafter include situations where planes of skewer boards are themselves tangent to the solid arc.

Fig. 3 illustrates also rather diagrammatically one of the possible mechanical embodiments of the arrangement represented in Fig. 2, and one that is well adapted for the present purpose. Reference characters like those of Fig. 3 are employed in Fig. 4.

Fig. 3 shows the two universal joints in perspective. The axis y_1 is formed by the journals 1, which are mounted in stationary bearings 2. The journals 1 are secured to the stirrup member 3 in which is rigidly mounted a rod 4 which embodies the axis x_1 . Rotatably mounted on the rod 4 by means of bearings 5 and 6 is a bracket 7 having an arm 8 to which the purn ejection chute L_1 is secured. The bracket 7 is also provided with an arm 8a. The stirrup member 3 also has an arm 3b with an eye 3c. The lower universal joint consists of the plate 14, which is provided with journals 15 pivotally mounted in stationary bearings 16 secured to the machine, and of the frame 18 pivotally mounted on the journals 17 of the plate 14. The journals 15 embody the axis y_2 and the journals 17 form the axis y_2 . The arm 19 is attached to the plate 14 and the arm 20 is rigidly attached to the frame 18. The lever 8a and the arm 20 are interconnected by the connecting rod V_2 through ball-and-socket joints and in the same way the arm 19 and the arm 3b are articulately interconnected by the connecting rod V_1 . If a purn skewer board H is now placed on the frame 18, the frame 18 will be pivoted when the arm 8a and the arm 3b are pivoted, so that the purn ejection chute L_1 is enabled to come into axial alignment with each skewer or peg S of the board H.

Fig. 5, like Fig. 3, shows the stirrup member 3 which is mounted in the bearings 2 in the direction of the axis y_1 by means of journals 1. The bearings 2 are integral with the side walls 50 and 51, Fig. 10, of the gearbox of the device. Rigidly mounted in the stirrup member 3 is the rod 4 which is supported in the eye 3a of the stirrup member 3. The rod 4 constitutes the axis x_1 . The bracket 7 is rotatably secured to the rod 4 by means of the bearings 5 and 6, said bracket 7 having an arm 8 to which the purn ejection chute L_1 is screwed. On the non-rotating rod 4 is mounted the swivelling joint member 9 with the pivot pin 10, to which the eye 25a of the two-armed lever 25 is articulated. The lever 25 is rotatably mounted on the pivot 26, which is rigidly seated in the walls 50 and 51, Fig. 10, and the other end 25b of said lever 25 is provided with a roller 27. The cam plate 29, which has

ten follower tracks $a-k$ arranged stepwise at varying distances from, and about, the shaft 28, is keyed to the shaft 28, which is journalled in the side walls 50 and 51, Fig. 10, of the gearbox. The lever 25 therefore pivots according to the differences in radius of the steps a to k . The movement of the lever 25 from step to step causes the rod 4 to pivot about the journals 1, so that the ejection chute travels from row to row of skewers, viz., from a to k , and from k via L_1 back to skewer 1 of row a , as shown by the diagram of travel, Fig. 8. During the course of one step of the stepped cam plate, the purn ejection chute L_1 remains at the same level. As, however, the purn ejection chute has a semicircular mouth, Fig. 4, for guiding the purn, it must execute a curvilinear motion L_2 , Fig. 4, in order not to foul the surrendered purn. For this purpose the follower track of the cam plate 29 is provided with notches 29a, with the result that the ejection chute does not travel in a straight line from one skewer to the next, but describes the arc L_2 , Fig. 4, which takes it out of reach of the skewered purn. The stirrup member 3 has an arm 3b to the end of which the draw-rod V_1 is secured via a ball-and-socket joint 3c, so that the intermittent movement of the purn ejection chute L_1 from a to k is at the same time transmitted to the plate 14, Fig. 3, of the universal joint of the purn skewer board.

To move the purn ejection chute along each row of skewers, a second cam plate 32, likewise keyed to the shaft 28, Fig. 11, and therefore rotating at the same angular velocity as the cam plate 29, is provided. Said cam plate 32 is provided on its circumference with five curves 33 and five curves 34. The path of the curves 33 from 1 to 5 serves to steer the ejection chute L_1 from skewer 1 to skewer 5, Fig. 8. From point 5 to point 6 the cam plate 29 produces the lateral travel for transferring the ejection chute L_1 to row b of skewers, Fig. 8, whereupon the path of the curves 34 from point 6 to point 10 guides the purn ejection chute from skewer 6 to skewer 10. The curves 33 and 34 are likewise provided with notches 33a which serve to provide the curvilinear movement of the purn ejection chute from skewer to skewer of the purn skewer board. To generate this movement, the roller 35 travels along the curved tracks 33 and 34, said roller 35 being secured to the arm 36a of the two-armed lever 36. The lever 36 is pivotally mounted on the pivot 26 and the arm 36b is provided with a ball-and-socket joint 37 to which the connecting rod 38 is articulated. Cast on to the arm 3 of the bracket 7 is an arm 8a having a branch arm 8b, Fig. 7, to which the connecting rod 38 is secured through a ball-and-socket joint 39. The end of the arm 8a is provided with a universal joint 42 in which the connecting rod V_2 is mounted. On rotation of the cam plate 32, therefore, the lever 36 pivots on the pivot pin 26 and transmits its movement via the connecting rod 38 to the arm 8a, which is connected to the ejection chute L_1 , with the result that the lateral pivotal movement from row to row of the ejection chute L_1 is generated. The connecting rod V_2 , which is connected to the frame 18, Fig. 3, of the universal joint, which frame carries the purn skewer board, transmits the lateral pivotal motion of the ejection chute L_1 to said board.

Figs. 9, 10 and 11 show the operative members which encompass the rotation of the two cam plates 29 and 32. In the side walls 50, 51 (Figs. 10 and 11) of the gearbox the shaft 28 is jour-

nalled. Keyed to the shaft 28 by means of key 28a are the cam plate 29 and a ratchet wheel 53 having the same number of teeth 53b as the pirn skewer board has skewers. Mounted on the ratchet wheel 53 are the cam plate 32 and a ring 70 with a gap 69. On the bosses or hubs 53a and 29a the eye 54 of the lever 55 is rotatably mounted. The lever 55 has an eye 56 to which a draw-rod 57 is pivotingly attached, said draw-rod 57 being connected to the control lever 58 of the gearbox 60 of a winding frame. The lever 55 is operated by the draw-rod 57 when a pirn is changed. Articulated to the eye 56a of the lever 55 is a picking pawl 62 which engages in the gaps 53c of the ratchet wheel 53. Also secured 15 pivotally, to the gearbox and arranged to pivot on a pivot pin 64 is a weighting stirrup 63 having a roller 65 which engages in the gaps 53c of the ratchet wheel 53. At each pirn change, the lever 55 is moved by the draw-rod 57, and one tooth 53b of the ratchet wheel 53 is picked by the pawl 62. The roller 65 locks the ratchet wheel 53 in the new position. On this rotary movement, the cam plates 29 and 32 are at the same time each stepped round by one tooth, with 25 the result that, as described, a motion of the pirn ejection chute from one skewer to the next and the corresponding motion of the pirn skewer board are accomplished. When all the skewers on the skewer board are occupied, the ratchet wheel 53 has performed a complete revolution and the feeler pawl 68, which is pivoted to the lever 72 provided with a drop-weight 73, drops through the gap 69 in the ring 70. For this purpose the lever 72 is pivotally mounted on the pivot pin 26, and the rod 76 is pivoted to the arm 74 of lever 72 by means of the pivot pin 75. The rod 76 has a loop 76a in which the pin 71 of the stop lever 78 of the winding frame 60 engages. Thus, when the feeler pawl 68 drops, the winding frame 60 is stopped by the rod 76, so that the now full pirn skewer board can be replaced by an empty one. Since the ratchet wheel 53 turns, when the winder is started up again, before the drop pawl 68 is lifted quite clear of the gap 69, 45 said pawl is pivotally attached to the lever 72 and held in position by the spring 68a, so that it can yield and jump on to the ring 70 as soon as it leaves the gap 69.

When the pirn skewer board has been changed, 50 the rod 76 is pressed down and the automatic pirn winder started again with the control lever 57. On the next pirn change the ratchet wheel 53 is again stepped round to the extent of one tooth by the pawl 62, when the roller 27 drops back 55 from cam step k to cam step a, so that the pirn ejection chute comes to rest in front of skewer 1. The return of the pirn ejection channel can also take place after the last pirn has been skewered.

Fig. 12 is a complete lateral elevation of the device connected to the automatic winder on a reduced scale in lateral elevation. In order to steady the individual movements of the pirn skewer board, a fluid dashpot 80 is provided 65 which is connected to one part of the universal joint.

We claim:

1. A device for depositing pirns onto skewers of a skewer board comprising a carrier for the skewer board, a pirn delivery device to deliver pirns to the skewers of a board on said carrier, and at least one universal joint to rock said carrier to rock a skewer board thereon into planes parallel to planes tangent to a solid arc and correlative move the discharge portion of said delivery device through said solid arc and to positions for delivery of pirns to skewers when the board is lying in said planes.

2. A device for depositing pirns onto a pirn skewer board comprising a carrier for the skewer board, a pirn delivery device to deliver pirns to the skewers of a board on said carrier, and at least one universal joint to move the delivery portion of said pirn delivery device substantially throughout a solid arc and correlative rock said carrier to rock a board thereon into planes substantially parallel to planes tangent to said solid arc at points on the arc adjacent momentary positions of the delivery portion of the pirn delivery device.

3. A device for depositing pirns onto a pirn board having skewers, comprising a carrier for the board, a chute to deliver pirns to the skewers of a board on said support, a universal joint pivoting the discharge end of said chute to swing substantially throughout a solid arc of a solid angle, said carrier being disposed at the opposite side of said solid arc from the apex of said solid angle, a universal joint to rock said carrier to rock a skewer board on said carrier into planes parallel to planes tangent to said solid arc to place skewers of the board substantially normal to said solid arc successively, and an interconnection connecting said universal joints for conjoint operation to direct the discharge end of said chute to adjacent whichever skewer is substantially normal to said arc at the moment.

4. The subject matter of claim 3, characterized by the fact that means are provided to direct the rocking of said carrier to carry a pirn board thereon from each of its planes to an adjacent plane successively substantially throughout said solid arc.

5. The subject matter of claim 4, characterized by the fact that the center about which said carrier rocks is located at substantially the center of the carrier, and the center about which said end of the chute swings is located in a straight line which passes through said center of rocking of the carrier and the center of the solid arc.

6. The combination of the subject matter of claim 3 with a pirn winder having a control member which operates on each change of pirn at the winder, said chute being disposed to receive wound pirns from said winder and said control member being connected to said universal joints to control the operation thereof.
